UNITED STATES PATENT OFFICE.

ORRELL ASHTON, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

RELASTING-MACHINE.

1,150,804.

Specification of Letters Patent. Patented Aug. 17, 1915.

Application filed November 2, 1914. Serial No. 869,844.

To all whom it may concern:

Be it known that I, ORRELL ASHTON, a citizen of the United States, residing at Swampscott, in the county of Essex and 5 State of Massachusetts, have invented certain Improvements in Relasting-Machines, of which the following description, in connection with the accompanying drawings, is a specification, like reference characters on 10 the drawings indicating like parts in the several figures.

This invention relates to machines known as relasting machines which are used particularly in the manufacture of turn shoes 15 for drawing the shoe over a last after the shoe has been turned, although obviously such machines are adapted to perform a like operation upon shoes of other types.

Among its novel and advantageous features the invention provides, in combination with a last support and a tool for engaging a shoe to pull the shoe over the last, operating means for the tool so constructed and arranged that the tool may be manipulated 20 freely through an extended range of movement in accordance with changes in the position of the last support or in applying said tool to shoes of various sizes and styles, and when applied to a shoe may be operated 25 without any material lost motion, whatever 30 may be its position with reference to the operating means.

As herein shown the invention includes an operating member in the form of a treadle 35 for actuating the tool and connecting means in the form of a flexible member extending from the tool to a guide on the treadle and thence to resilient means which tends to maintain the member taut and to uphold 40 the treadle while permitting the tool to be moved to different positions through longitudinal movement of the flexible member, the treadle having means for fixing its relation to the flexible member to establish 45 an effective connection with the tool when the treadle is operated to pull the tool.

The various features of the invention, including certain details of construction and combinations of parts, will now be described 50 with reference to the accompanying drawings and pointed out in the claims.

In the drawings, Figure 1 is a perspective view of a machine in which the invention is embodied; Fig. 2 is a detail view illustrating 55 the means for establishing an operative

connection between the treadle and the flexible member that leads to the shoe pulling tool; Fig. 3 illustrates the application of a modified form of tool to a low shoe; Fig. 4 illustrates the manner in which the tool shown in Fig. 1 is applied to a high shoe, and Fig. 5 is a cross-section on the line 5—5 of Fig. 2.

The machine includes a base or frame 2 in which is mounted adjustably an upright 65 jack 4 for supporting the various lasts in position for the respective shoes to be drawn thereover.

A bracket 6 on the jack serves to support a work table or tray 8, and the tray has 70 secured thereto a bracket 10 which is slotted to receive the shoe pulling tool and maintains the tool in a position convenient to the hand of the operator. This tool comprises a pair of levers 12 pivoted together 75 at 14 and having their shoe engaging ends shaped to secure an effective hold upon the upper of a shoe without injuring the shape or appearance of the upper.

In the form shown in Figs. 1 and 4 the 80 ends of the levers are shaped for gripping the upper of a high shoe in the manner illustrated in Fig. 4, while the tool shown in Fig. 3 is shaped for gripping a low cut shoe 85 and includes a horn 16 for guiding the shoe over the heel end of the last. The shoe engaging ends or jaws of the tool in both forms are normally maintained closed by means of a spring seen at 18 in Fig. 3, the jaws being opened by hand pressure applied 90 to the rear portions of the levers 12 at the other side of the pivot 14. In pulling a shoe these portions of the levers are positively separated to cause the jaws to maintain an effective hold upon the shoe by means of 95 toggle links 20 connected together by a pivot pin 22 which is guided in a slot in a link 24 mounted on the pivot 14. The toggle is so arranged as not to be entirely straightened by the pull upon the shoe, so that the 100 tool may be readily disengaged from the shoe by the operator's hand. It will be evident that with this arrangement the pressure with which the tool grips the shoe will be proportionate to the strength of the pull 105 upon the tool in drawing the shoe over the last.

The connections for operating the toggle and pulling the tool comprise a yoke 26 connected to the pivot 22, a hook 28 swiveled 110

in the yoke, and a chain 30 extending from the hook under a pulley 32 on a treadle 34 which is pivoted to the frame at 36. The chain is connected at its opposite end to a swinging arm 38 pivotally mounted upon a lug 40 on the treadle and swung normally by a spring 42 in a direction to hold the chain 30 taut and support the treadle at its upper limit of movement which is variably determined by a stop 44 that may be inserted in any one of a number of holes 46 in the frame 2.

The treadle 34 has at its forward end a tread member 48 pivoted at 50 and carrying 15 a forked guide 52 which positions the member with reference to opposite sides of the pulley 32; and between the forks of the guide 52 is a dog 54 which engages a link of the chain and fixes the position of the 20 chain with reference to the treadle when the latter is operated. A spring-held plunger 56 engaging a pin 58 serves to position the tread member normally with the dog 54 out of engagement with the chain.

25 With the machine constructed as described it will be apparent that the operating means for the shoe gripping tool comprises a flexible connection which permits the tool to be moved in any direction and is extensible 30 with reference to the operating treadle so that the tool may be positioned at various distances from the treadle in applying it to a shoe. With the tool in engagement with a shoe in the manner illustrated in Fig. 3 or 35 in Fig. 4, the operator depresses the treadle, the engagement of the foot with the tread member 48 serving first to lock the chain to the treadle by means of the dog 54 and the subsequent movement of the treadle exerting 40 a downward pull upon that portion of the chain which extends between the treadle and the tool. The operation of the treadle thus serves to effect without any lost motion a positive pull upon the tool, spreading the 45 toggle 20 to insure firm engagement of the tool with the shoe and pulling the shoe quickly over the last. When the pressure upon the treadle is released the dog 54 first disengages the chain, and through the tension of the spring 42 the chain then serves 50 to lift the treadle as far as permitted by the stop 44 and to maintain it in its uppermost position. The tool may then be disengaged from the shoe and restored to the holder 10 55 to await the removal of the shoe, the mounting of another last on the jack 4 and the location of another shoe in position for treatment.

Although the preferred arrangement shown 60 and described includes a foot treadle for operating the shoe pulling tool, it will be readily understood that many features of the invention are not dependent upon the use of this precise form of operating member, and 65 that the term treadle as employed in many

of the claims is to be construed as comprehending a broad range of equivalents.

Having described the invention, what I claim as new and desire to secure by Letters Patent of the United States is the following:

1. In a machine of the class described, the combination with a last support, of a shoe pulling tool, a member for operating the tool to pull a shoe over a last upon the support, connecting means between the tool and said member extensible to vary the distance therebetween, and means for preventing extension of said connecting means during the pulling operation.

2. In a machine of the class described, the combination with a last support, of a shoe pulling tool, a member for operating the tool to pull a shoe over a last upon the support, a connection between the tool and said member extensible to vary the distance therebetween, and means on the member for engaging said connection to prevent such extension thereof during the operation of the member.

3. In a machine of the class described, the combination with a last support, of a shoe pulling tool, a treadle for operating the tool to pull a shoe over a last upon the support, a connection between the tool and the treadle movable with reference to the treadle to vary the distance between the treadle and the tool, and means on the treadle constructed and arranged to engage said connection automatically upon the operation of the treadle to prevent such movement of the connection with reference to the treadle during the operation of pulling the shoe.

4. In a machine of the class described, the combination with a last support, of a shoe pulling tool, a treadle for operating the tool to pull a shoe over a last upon the support, a connection between the tool and the treadle movable with reference to the treadle longitudinally to lengthen the distance between the treadle and the tool, resilient means tending to move the connection and the tool longitudinally with reference to the treadle in the opposite direction, and means for preventing longitudinal movement of said connection with reference to the treadle during the pulling operation.

5. In a machine of the class described, the combination with a last support, of a shoe pulling tool, a treadle for operating the tool to pull a shoe over a last upon the support, a flexible connection between the tool and the treadle movable while the treadle is in idle position to permit the tool to be located at different distances from the treadle, and means for preventing such movement of said connection during the operative movement of the treadle.

6. In a machine of the class described, the combination with a last support, of a shoe

pulling tool, a treadle for operating the tool to pull a shoe over a last upon the support, a connection between the tool and the treadle comprising a chain connected to the tool and movable to permit the tool to be positioned at different distances from the treadle, and means on the treadle constructed and arranged to engage the chain to effect a rigid connection therewith during the operative movement of the treadle.

7. In a machine of the class described, the combination with a last support, of a shoe pulling tool, a treadle for operating the tool to pull a shoe over a last upon the support, a guide on the treadle, a flexible member connected to the tool and engaging said guide and normally movable lengthwise with reference to the guide, and means for fixing the lengthwise position of said member with reference to the guide upon the operation of the treadle.

8. In a machine of the class described, the combination with a last support, of a shoe pulling tool, a treadle for operating the tool to pull a shoe over a last upon the support, a guide on the treadle, a flexible member connected to the tool and engaging said guide, means for holding said member taut while permitting it to move normally lengthwise with reference to the guide, and means for preventing lengthwise movement of said member over the guide during operative movement of the treadle.

9. In a machine of the class described, the combination with a last support, of a shoe pulling tool, a flexible member connected to the tool, resilient means for holding said member taut, and operating means for the tool arranged to engage said member between the tool and said resilient means to cause the tool to pull a shoe over a last upon the support.

10. In a machine of the class described, the combination with a last support, of a manually supportable shoe pulling tool, a flexible member connected at one end to the tool, a pivoted arm connected to the other end of said flexible member, resilient means for swinging said arm in a direction to hold said member taut while permitting the tool to be moved to different positions, and positive means for engaging and pulling said member in the same direction as said resilient means to cause the tool to pull a shoe over a last upon the support.

11. In a machine of the class described, the combination with a last support, of a shoe pulling tool, a treadle for operating the tool to pull a shoe over a last upon the support, a guide on the treadle, a flexible member connected to the tool and extending under said guide to support the treadle, and resilient means arranged to hold said member taut and maintain the treadle normally at its upward limit of movement.

12. In a machine of the class described, the combination with a last support, of a shoe pulling tool, a treadle for operating the tool to pull a shoe over a last upon the support, connections between the tool and the treadle comprising a flexible member and resilient means for holding said member taut and supporting the treadle, and means for variably limiting the extent of upward movement of the treadle.

75
13. In a machine of the class described, the combination with a last support, of a shoe pulling tool, a treadle for operating the tool to pull a shoe over a last upon the support, a connection between the tool and the treadle movable normally lengthwise with reference to the treadle, said treadle having a tread member movable with reference to other portions thereof, and means operated by said member for fixing the lengthwise position of said connection with reference to the treadle upon an operative movement of the treadle.

80
14. In a machine of the class described, a shoe pulling tool constructed and arranged for bodily manipulation manually, a member for operating the tool, a flexible connection between the tool and said member movable to permit the tool to be positioned at different distances from said member, means 90 for supporting the tool when the tool is not in use, and means for holding said connection taut in all positions of the tool.

95
15. In a machine of the class described, a last support, a shoe pulling gripper adapted and arranged for bodily manipulation manually to engage a shoe on the support, a treadle lever, a chain extending from the gripper and movable through a guide in the treadle lever, tensioning means to which the free end of the chain is connected to hold it taut, and means carried by the treadle lever to grip the chain automatically when the treadle lever is depressed.

100
110
16. In a machine of the class described, a last support, a shoe pulling gripper adapted and arranged for bodily manipulation manually to engage a shoe on the support, means for holding the gripper normally closed, a treadle lever, a connector extending from the gripper to the treadle lever, and a foot piece movable on the treadle lever and arranged to grip the connector when the foot piece is moved and thereafter to depress the treadle lever for actuating the tool to pull over the last the shoe with which the tool has been engaged.

115
120
125
130
17. In a machine of the class described, a base, an upright extending therefrom, a last support on the upright, a shoe pulling tool adapted to engage the heel portion of a shoe to pull the shoe over its last, a flexible connector attached to the tool, an operating treadle having a guide for the connector, an arm extending rearwardly from the upright

and to which the treadle is pivoted, means for holding the connector taut and acting through the guide to hold the treadle up-raised, and means on the treadle for gripping the connector and causing it to transmit movement to the tool.

18. In a machine of the class described, a base, an upright extending therefrom, a last support on the upright, a shoe pulling tool adapted to engage the heel portion of a shoe to pull the shoe over its last, a flexible connector attached to the tool, an operating treadle to which the connector extends, a work table located relatively to the shoe support and to the treadle to be out of the course of the connector when the tool is being operated, and a tool holder on the table constructed and arranged to engage the tool

and restrain it from displacement by the action of the connector and the treadle while the tool is not in use.

19. In a machine of the class described, a base, an upright extending therefrom, a last support on the upright, a table, a tool holder on the table, a shoe pulling tool, a flexible connector attached to the tool, and an operating treadle to which the connector extends.

In testimony whereof I have signed my name to this specification in the presence of two subscribing witnesses.

ORRELL ASHTON.
